ISAAC SNOW, OF LAWRENCE, MASSACHUSETTS, ASSIGNOR, BY MESNE ASSIGNMENTS,
TO DRAPER CORPORATION, OF HOPEDALE, MASSACHUSETTS, A CORPORATION OF
MAINE.

TRANSFERRER FOR AUTOMATIC FILLING-REPLENISHING LOOMS.

1,214,384.

Specification of Letters Patent. Patented Jan. 30, 1917.

Application filed July 3, 1916. Serial No. 107,220.

To all whom it may concern:

Be it known that I, ISAAC SNOW, a citizen of the United States, and resident of Lawrence, in the county of Essex and State of Massachusetts, have invented an Improvement in Transferrers for Automatic Filling-Replenishing Looms, of which the following description, in connection with the accompanying drawing, is a specification, like characters on the drawing representing like parts.

This invention relates to the transferrer of looms provided with automatic filling replenishing mechanism. In such looms the supply of fresh filling carriers is maintained in a feeder or hopper and when the call comes for replenishment, a pivoted transferrer is moved downwardly and acts to transfer a fresh filling carrier from the hopper into the shuttle which is then beneath the hopper on the lay. The transferrer usually contacts with the butt of the filling carrier and also with a point at or adjacent the tip but the main force applied by the transferrer is to the butt. As a result and as the filling carrier is not positively held by the transferrer, the filling carriers are sometimes improperly placed in the shuttle by the transferrer and sometimes the filling carrier is not properly seized or acted upon by the transferrer during the transfer operation. In either case breakage occurs.

It is the object of the present invention to provide a form of transferrer which upon transfer movement will come into contact with the fresh filling carrier both at the butt and at or adjacent the tip and which will be provided with a means for positively locking the tip of the filling carrier to the transferrer so that the filling carrier will be transferred accurately and surely into the shuttle.

The nature of the invention will appear more fully from the accompanying description and drawings and will be particularly pointed out in the claims.

The drawings illustrate so much of the mechanism of an automatic filling replenishing loom and the preferred form of the invention embodied therein as is necessary to a disclosure of the said invention.

In the drawings: Figure 1 is a side elevation partially in cross-section of the hopper stand, hopper, transferrer and immediately connected parts of a loom of the well known Northrop type; Fig. 2 is a rear elevation of the transferrer; Fig. 3 is a side elevation of the transferrer as shown in Fig. 2 with the transferrer shown engaging and gripping a filling carrier; Fig. 4 is a bottom plan view of a portion of the transferrer as shown in Fig. 2.

Since this invention relates solely to the transferrer, it is unnecessary to illustrate or to describe in detail the automatic filling replenishing loom of which it forms a part and of which the construction and operation is familiar to those skilled in the weaving art.

For convenience of illustration, there is herein shown the hopper stand 1 from which rises the hopper 2 and upon which are rotarily mounted the disks, one of which 3 is shown. The disk 3 is provided with peripheral seats 4 in which are mounted the butts of the supply of fresh filling carriers 5 while the tips are mounted or supported in the opposite disk not illustrated.

The filling carrier to be transferred is brought by the rotation of the hopper into contact with the abutment 6 and in this position is held in the hopper by the yielding bobbin support 7. When the running filling breaks or becomes entirely or partially exhausted and filling replenishment is called for, mechanisms are set into operation which cause the transfer of this filling carrier resting against the abutment 6 from the hopper downwardly into the shuttle which is then on the lay and beneath the hopper, the spent filling carrier being simultaneously ejected.

The immediate instrumentality concerned in the transfer is the so-called transferrer which is herein shown as pivotally mounted at 8 on the hopper stand, and of the shape of a bell crank lever. The transferrer projects between the disks of the hopper and in its normal inactive position the head 9 of the transferrer extends directly above the butt of the filling carrier in position for transfer.

In the construction illustrated as embodying the present invention, the head 9 of the transferrer has extending laterally therefrom in the direction of the tip of the filling

carrier, an arm 10 bent downwardly at its free end and recessed at 11. The proportions are such that when the transferrer comes into contact with the filling carrier 5 and the head 9 contacts with the butt, the recess 11 will engage the filling carrier at the tip. A rock shaft 12 is journaled in the head 9 and extends in general parallelism with said arm and is preferably journaled 10 in the depending end of the arm 10. This rock shaft 12 is provided adjacent the end of the arm 10 and adjacent the recess 11 with a finger 13 curved at its lower end to conform in general with the curvature of the recess and the curvature of the tip of the filling carrier.

A tail piece 14 projects from the shaft 12 adjacent the head, extends beneath the head and fits within a recess 15 in the bottom of 20 the head. As illustrated, this tail piece 14 projects downwardly from the shaft 12, then rearwardly and then laterally beneath the head. A helical spring 16 is mounted on the shaft 12 and secured at one end to a collar 17 25 adjustable by a set screw 18 on the rock-shaft and is secured at its opposite end 19 to the transferrer arm. This spring acts normally to maintain the rock-shaft in the position shown in Figs. 1 and 2 with the tail piece 14 30 below the plane of the bottom of the head 9 and with the finger 13 forward of the recess 11.

The operation of the parts will now be apparent. Upon the call for filling replenishment, the transferrer is thrown downwardly. 35 As it moves downward the tail piece 14 comes into contact with the butt of the filling carrier and the recess 11 passes over the tip. As the movement continues, the tail piece 14 40 passes into the recess 15 in the head of the transferrer and the finger 13 closes against the tip now in the recess 11 locking it within said recess. As the movement continues, the transferrer head acting against the butt and 45 the recessed end of the arm 10 acting against the tip forces the filling carrier out from the hopper and the transfer movement is completed with the filling carrier locked to the transferrer by the finger 13. Thus the filling 50 carrier is transferred accurately and surely into its proper position in the shuttle and all danger of breakage from improper positioning of the filling carrier during transfer is eliminated. Upon initiation of reverse movement of the transfer, the spring 16 rocks the rock shaft 12 causing the finger 13 to swing away from the recess and the filling carrier 55 is thus automatically released.

Having fully described my invention, what

I claim as new and desire to secure by Letters 60 Patent is:

1. In a loom provided with automatic filling replenishing mechanism, a hopper containing a supply of fresh filling carriers, a transferrer movable on the call for filling replenishment to transfer a filling carrier from the hopper into the shuttle, the said transferrer comprising a head operating at the butt of the filling carrier, an arm extending laterally from said head and recessed at its 65 end to engage the tip of the filling carrier, a rock shaft journaled in said head and extending in general parallelism with said arm, a finger projecting from said shaft adjacent the end of the arm, a tail piece projecting 70 from said shaft and extending beneath the head, and means acting normally to rock the shaft and maintain the tail piece out of engagement with the head and the finger away from the recess, whereby as the transfer 75 movement takes place the said shaft is rocked by the butt of the filling carrier engaging the tail piece to cause the finger to engage the tip and lock it within said recess, and whereby upon initiation of the reverse movement of the transferrer the filling carrier is 80 automatically released.

2. In a loom provided with automatic filling replenishing mechanism, a hopper containing a supply of fresh filling carriers, a 90 transferrer movable on the call for filling replenishment to transfer a filling carrier from the hopper into the shuttle, the said transferrer comprising a head operating at the butt of the filling carrier, an arm extending 95 laterally from said head and recessed at its end to engage the tip of the filling carrier, a rock shaft journaled in said head and extending in general parallelism with said arm, a finger projecting from said shaft adjacent 100 the end of the arm, a tail piece projecting from said shaft and extending beneath the head, and a helical spring on said shaft connected at one end thereto and at the other end to said head and acting normally to rock 105 the shaft and maintain the tail piece out of engagement with the head and the finger away from the recess, whereby as the transfer movement takes place the said shaft is rocked by the butt of the filling carrier 110 engaging the tail piece to cause the finger to engage the tip and lock it within said recess, and whereby upon initiation of the reverse movement of the transferrer the filling carrier is 115 automatically released.

In testimony whereof, I have signed my name to this specification.

ISAAC SNOW.
